[57] CLAIM

The ornamental design for surface ornamentation for a shoe outsole bottom, as shown and described.

DESCRIPTION

FIG. 1 is a plan view of surface ornamentation for a shoe outsole bottom in accordance with my new design; and

FIG. 2 is a plan view of surface ornamentation for a shoe sole bottom in accordance with another embodiment of my new design.

The broken line showing of a shoe sole bottom perimeter is for illustrative purposes and forms no part of the claimed design.

FIG. 2.
